UNITED STATES PATENT OFFICE.

HERRIOTT S. WARNOCK, OF CHICAGO, ILLINOIS.

PRINTING-ELEMENT HOLDER.

1,418,112.

Specification of Letters Patent. Patented May 30, 1922.

Application filed November 3, 1921. Serial No. 512,419.

To all whom it may concern:

Be it known that I, HERRIOTT S. WARNOCK, citizen of the United States, residing at Chicago, in the county of Cook and State of Illinois, have invented a certain new and useful Improvement in Printing-Element Holders, of which the following is a full, clear, concise, and exact description.

My invention relates to printing element holders, commonly termed printing plate holders, and has for one of its objects the provision of improved mechanism entering into the construction of the holder so that the holding jaw thereof may readily be applied to a plate or other printing element to be clamped thereby.

In practicing this feature of my invention I employ a hollow carrier, a clamping jaw upon the carrier and having a stem within and in pivotal connection with the carrier, and mechanism serving to turn the jaw and having complementary elements preferably in sliding engagement, one of these elements being upon the carrier and the other assembled with the clamping jaw. In the preferred embodiment of the invention there is a screw assembled with the jaw and extending along the stem of the jaw, the jaw having an opening in line with the screw to afford access to the screw, and a nut upon the screw, the carrier having inclined opposite slots between which the nut is disposed and in which the nut has engagement with the carrier.

The invention has for another of its objects the provision of improved means for assembling the carrier with a printing foundation. In carrying out this object of my invention there is a clamping jaw upon the carrier, a retaining member assembled with the carrier and movable transversely thereof into and out of engagement with the foundation, and an actuating element movable transversely of the foundation, the retaining member and actuating element having engaging portions that have relative movement in an inclined direction to effect movement of the retaining member into and out of engagement with the foundation.

I will explain my invention more fully by reference to the accompanying drawings showing the preferred embodiment thereof and in which Fig. 1 is a vertical sectional view on a larger scale of a printing plate holder constructed in accordance with the invention and a portion of the printing plate

foundation that receives the holder; Fig. 2 is a sectional view on line 2-2 of Fig. 1; Fig. 3 is a plan view of the printing plate holder; Fig. 4 is a sectional view on line 4-4 of Fig. 3; Fig. 5 is a plan view showing a portion of a section of a printing plate foundation with a printing plate holder of my invention assembled therewith; Fig. 6 is a view showing parts of the printing plate holder in separated relation; Fig. 7 illustrates other parts of the printing plate holder in separated relation; and Fig. 8 illustrates an adjusting tool for effecting the assembly and separation of the printing plate holder and printing foundation.

Like parts are indicated by similar characters of reference throughout the different figures.

The printing bed or foundation may be of any suitable shape, the drawings showing a section 1 of a flat bed, a number of sections suitably assembled forming the bed. Each of these sections or blocks is formed with a plurality of cylindrical holes 2, in the construction of the bed section illustrated, although it is to be understood that the invention is not to be limited to any particular form of bed not to the shape of the holes 2 therein. As illustrated, each hole is provided with an annular enlargement 3 below the work supporting face of the bed whereby there is provided in each hole an annular retaining shoulder 4. Carriers 5 are used in sufficient number to hold the printing plate upon the bed, these carriers supporting the work engaging mechanism that is to be described. The carriers are shown as being formed of two parts of U-form, one part being interposed between the sides of the other and the bases of both parts being cylindrically curved. These U-shaped parts are preferably assembled in part by rivets 5' and in part by an element of the mechanism that will later be described. The carriers 100 are snugly received within the holes within which they are rotatable in order that the work engaging mechanism may be positioned to suit the location of the work that is to be held upon the foundation.

My improved mechanism for holding the carrier in assembly with the bed is inclusive of an actuating element 6 within the carrier and slideable along the same, this actuating element having two wings 7 each formed with an inclined slot 8, the slots being in the same inclined plane and receiving a pin

9 that is carried by the upright wings 10 of a retaining member 11. Said wings 10 are formed with horizontal elongated slots or openings 12 through which the rod 13, that is within and anchored to the shell, is passed. This rod passes through the overlapping sides of the sections of the shell and takes part in maintaining them in assembly as indicated most clearly in Fig. 2. The actuating element 6 is formed with an opening 14 for the reception of a projection 14' upon a suitable actuating tool, such as that shown in Fig. 8, whereby movement of the actuating element may be forced. When the actuating element is drawn to its outermost position the lower portions of the slots 8 are positioned to receive the pin 9. Said pin, being fixed upon the wings 10 and virtually constituting a part of the retaining member, will force the inward movement of these wings as the pin is brought to the lower ends of the slots 8 whereby the retaining member is withdrawn sufficiently into the carrier 5 to permit of the insertion 25 and removal of the same. When the carrier is to be assembled with the printing plate foundation it is lowered to a position in which the plane of the retaining member 11 is below the shoulder 4, the actuating element 6 being then withdrawn to its uppermost position to withdraw the retaining member sufficiently into the shell to permit it to clear the bed. When the retainer is thus positioned the actuating element is depressed to cause the upper ends of the slots 8 to receive the pin 9 in which operation the wings 10 are moved outwardly to thrust the retaining member 11 beneath the retaining shoulder 4 upon the bed. When the 30 parts are thus assembled the plate holding mechanism, now to be described, may be suitably adjusted.

This plate holding mechanism is inclusive of a clamping jaw 15 upon the carrier 5 and having a bifurcated stem 16 within and in pivotal connection with the carrier, the stem desirably being pin pivotal or rotative connection with the rod 13 that is surrounded by the lower end of the stem. A screw 17 extends along the stem of the jaw transversely of the printing foundation. It is journaled at its lower end in a block 18 that itself is journaled upon the horizontal rod 13. The upper end of the screw carries an element 19 that is polygonal in contour, this portion of the screw passing through an opening 20 in line with the screw and through which opening the portion 19 of the screw may be engaged by the upper (key) 55 end of the adjusting tool shown in Fig. 8. A nut 21 is upon the screw, this nut having lateral extensions 22 that are receivable within the inclined opposite slots 23 between which the nut is disposed and in which the 60 nut has sliding engagement with the car-

rier. As the screw 17 is turned the nut is moved in one direction or the other along the stem of the jaw and as the nut is thus moved the inclined slots 23 serve to confine it to an inclined direction of movement 70 which causes movement of the jaw 15 along the foundation to an extent proportional to the movement of the nut along the screw. The nut is also flattened at the jaw stem 16 to supplement the action of the slots 23 and 75 the nut projections 22 in preventing the nut from turning. As the nut is moved longitudinally of the shaft without turning, the mounting 18 for the screw 17 turns upon the rod 13 in company with the stem of the jaw. 80

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. A printing element holder including a 90 hollow carrier; a clamping jaw upon the carrier and having a stem within and in pivotal connection with the carrier; and mechanism serving to turn the jaw and having complemental elements in sliding engagement, one of these elements being upon the carrier and the other assembled with the clamping jaw.

2. A printing element holder including a 100 hollow carrier; a clamping jaw upon the carrier and having a stem within and in pivotal connection with the carrier; and mechanism serving to turn the jaw and having complemental elements in sliding engagement, one of these elements being upon 105 the carrier and the other assembled with the clamping jaw, the path of relative movement of said complemental elements being inclined.

3. A printing element holder including a 110 hollow carrier; a clamping jaw upon the carrier and having a stem within and in pivotal connection with the carrier; a screw assembled with the jaw and extending along the stem of the jaw; and a nut upon the 115 screw that is in sliding engagement with an inclined portion upon the carrier.

4. A printing element holder including a 120 hollow carrier; a clamping jaw upon the carrier and having a stem within and in pivotal connection with the carrier; a screw assembled with the jaw; and a nut upon the screw that is in sliding engagement with an inclined portion upon the carrier.

5. A printing element holder including a 125 hollow carrier; a clamping jaw upon the carrier and having a stem within and in pivotal connection with the carrier; a screw assembled with the jaw and extending along the stem of the jaw, the jaw having an open- 130

ing in line with the screw to afford access to the screw; and a nut upon the screw that is in sliding engagement with an inclined portion upon the carrier.

5 6. A printing element holder including a hollow carrier; a clamping jaw upon the carrier and having a stem within and in pivotal connection with the carrier; a screw assembled with the jaw; and a nut upon the 10 screw, the carrier having inclined opposite slots between which the nut is disposed and in which the nut has engagement with the carrier.

7. A printing element holder including a 15 hollow carrier; a clamping jaw upon the carrier and having a stem within and in pivotal connection with the carrier; a screw assembled with the jaw and extending along the stem of the jaw; and a nut upon the 20 screw, the carrier having inclined opposite slots between which the nut is disposed and in which the nut has engagement with the carrier.

8. A printing element holder including a 25 hollow carrier; a clamping jaw upon the carrier and having a stem within and in pivotal connection with the carrier; a screw assembled with the jaw and extending along the stem of the jaw, the jaw having an opening in line with the screw to afford access to the screw; and a nut upon the screw, the carrier having inclined opposite slots between which the nut is disposed and in which the nut has engagement with the carrier.

35 9. The combination with a foundation; of a carrier, said foundation being formed to receive said carrier; a clamping jaw upon the carrier; a retaining member assembled with the carrier and movable transversely 40 thereof into and out of engagement with said foundation; and an actuating element movable transversely of the foundation, said retaining member and actuating element having engaging portions that have relative 45 movement in an inclined direction to effect

movement of the retaining member into and out of engagement with the foundation.

10. The combination with a foundation; of a carrier, said foundation being formed to receive said carrier; a clamping jaw upon the carrier; a retaining member assembled with the carrier and movable transversely thereof into and out of engagement with said foundation; and an actuating element movable transversely of the foundation, 50 said actuating element having an inclined slot, and said retaining member having a portion entering said slot, whereby upon operation of the actuating element the retaining member is moved into or out of engagement with the foundation. 55

11. The combination with a foundation; of a carrier, said foundation being formed to receive said carrier; a clamping jaw upon the carrier; a retaining member assembled 60 with the carrier and movable transversely thereof into and out of engagement with said foundation; and an actuating element movable transversely of the foundation, said actuating element having two wings between 65 which the retaining member is disposed, said wings having inclined slots in which portions of the retaining member are received, whereby upon operation of the actuating element the retaining member is 70 moved into or out of engagement with the foundation. 75

12. A printing plate holder including a hollow carrier; a clamping jaw upon the carrier and having a stem within and in 80 pivotal connection with the carrier; and mechanism serving to turn the jaw, this mechanism having complementary elements that have relative movement in an inclined direction to effect turning movements of the 85 jaw.

In witness whereof, I hereunto subscribe my name this 25th day of October A. D., 1921.

HERRIOTT S. WARNOCK.
